CLAIM

The ornamental design for a spice bottle holder, as shown and described.

DESCRIPTION

FIG. 1 is a perspective view of a spice bottler holder, showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another top, front, right perspective view of the spice bottle holder of FIGS. 1-7, shown with environment. The broken lines in FIGS. 1-3 and 8 illustrate portions of the spice bottle holder which form no part of the claimed design. The remaining broken lines, shown in the FIG. 8 view, are directed to environment, which forms no part of the claimed design.

1 Claim, 8 Drawing Sheets---
